UNITED STATES PATENT OFFICE.

JOHN A. CLARK, OF WORCESTER, MASSACHUSETTS, AND JAMES K. DALKRANIAN, OF WEEHAWKEN HEIGHTS, NEW JERSEY; SAID DALKRANIAN ASSIGNOR TO UNITED STATES PERSIAN CARPET COMPANY, A CORPORATION OF NEW YORK, AND SAID CLARK ASSIGNOR TO CROMPTON & KNOWLES LOOM WORKS, A CORPORATION OF MASSACHUSETTS.

PILE OR TUFT FABRIC LOOM.

1,077,241.

Specification of Letters Patent.

Patented Oct. 28, 1913.

Application filed February 24, 1912. Serial No. 679,621.

To all whom it may concern:

Be it known that we, JOHN A. CLARK and JAMES K. DALKRANIAN, citizens of the United States, residing, respectively, at 5 Worcester, in the county of Worcester and State of Massachusetts, and Weehawken Heights, in the county of Hudson and State of New Jersey, have jointly invented certain new and useful Improvements in Pile or 10 Tuft Fabric Looms, of which the following is a specification.

Our invention relates to a tuft fabric loom, and more particularly to improvements in a pile or tuft fabric loom of the class shown 15 and described in U. S. Letters Patent, No. 446,402, wherein is shown cams to move the warps to form sheds, and mechanism to raise and lower the tuft yarn tubes or needles to introduce tuft yarn into the 20 warps. In said patented loom, the tuft yarns for forming the pile are inserted into the warps by a series of needles, each of which carries a tuft yarn, which is interwoven into the fabric, and then cut to form 25 the pile.

The object of our invention is to provide a new and improved method of making woven pile fabrics of the Persian rug type, the fabric having Persian knots, which are 30 formed mechanically by automatic mechanism, and preferably on a loom of the class above referred to.

In our improvements, to be hereinafter described, the Persian knot, so-termed, in 35 the fabric, is formed by inserting the pile yarn, and passing the pile yarn twice between the ground warp threads, which threads are moved sidewise or transversely of each other, by means of a comb placed between the lay and the fell of the cloth, and moved by cams, and crossed and uncrossed alternately, relatively to the movement of the pile yarn, which is put into the fabric, with its ends projecting below the surface of 40 the fabric, and before the tubes or needles carrying the tuft yarns, are withdrawn from the fabric, the tuft yarns are cut by a rotating cutter drawn transversely across the width of the fabric, and preferably upon 45 the lower side of the fabric.

Our invention consists in certain novel features of construction of our improvements as will be hereinafter fully described.

We have only shown in the drawings a detached portion of a tuft pile fabric loom 55 of the class referred to, with our improvements combined therewith, sufficient to enable those skilled in the art to understand the construction and operation thereof.

Referring to the drawings: Figure 1 is a 60 front view of a tuft fabric loom, and also a section, on line 1, 1, Fig. 2, looking in the direction of arrow *a*, same figure, showing our improvements detached. Fig. 2 is a side or end view of a detached portion of the 65 loom, and of our improvements, looking in the direction of arrow *b*, Fig. 1. Fig. 3 is, on an enlarged scale, a section, on line 3, 3, Fig. 1, looking in the direction of arrow *c*, same figure. Fig. 4 corresponds to Fig. 3, 70 but shows some of the parts shown in Fig. 3 in a different position. Fig. 5 is a diagrammatic view, showing the shed formed, and the combs moved upwardly above the lower warp. Fig. 6 shows a top or plan 75 view of the parts shown in Fig. 5, looking in the direction of arrow *d*, same figure; the tuft yarn needle and tuft yarn, shown in Fig. 5, are not shown in this figure. Fig. 7 corresponds to Fig. 6, but shows the combs moved sidewise, for a distance of two dents 80 of the reed, to cross the lower warps. Fig. 8 corresponds to Fig. 5, but shows the combs raised and extending above the upper warps. Fig. 9 is a plan view of the parts shown in 85 Fig. 8, looking in the direction of arrow *e*, same figure, and showing the combs moved halfway back, in the direction indicated by arrow *f*; the tuft yarn needle, and tuft yarn, shown in Fig. 8, are not shown in this figure. 90 Fig. 10 corresponds to Fig. 8, but shows the combs parted, to allow a tuft yarn needle, carrying a tuft yarn, to be lowered between the combs, and between the crossed warps. Fig. 11 is a plan view of the parts shown in 95 Fig. 10, looking in the direction of arrow *g*, same figure. Fig. 12 corresponds to Fig. 10, but shows the combs lowered and withdrawn from the warps. Fig. 13 corresponds to Fig. 12, but shows the tuft yarn needle 100

inserted a second time, to finish the loop of the tuft yarn, and, Fig. 14 shows the finished loop of the pile fabric, after the pile or tuft yarn has been cut or severed.

In the accompanying drawings, 1 is the loom side or end frame, 2 is a transverse girt, 3, Fig. 2, the breast beam, over which the fabric 4 passes to the take-up roll 5. In Fig. 2, 4' shows the piles or tufts on the lower side of the fabric, which are formed by inserting the tuft yarns 6, through the dropping of the tuft yarn tubes or needles 7. The lay 8 is provided with a reed 9, comprising dents through which the upper warps 10 and the lower warps 11 are passed from warp beams at the rear of the loom, not shown. The warps 10 and 11 are passed over whip rolls 12 and 13, see Fig. 2, which are mounted in levers 14 and 15, having their hubs secured on the transverse shafts 16 and 17. Cam levers 18 and 19 have their hubs 18' and 19', respectively, fast on the ends of the shafts 16 and 17. The cam lever 18 carries a roll 20, and the cam lever 19 carries a roll 21, which rolls are respectively adapted to engage, in this instance, the peripheries of the cams 22 and 23, which in this instance are fast on the bottom shaft 24.

All of the above mentioned parts may be of the usual and well known construction.

We will now describe our improvements, which relate particularly to the comb motion or warp parting device, to form the loops or knots of the pile or tuft yarns, which are inserted between the warps. The comb motion or warp parting device consists in this instance of two lifter bars 25 and 26 below the warps, see Fig. 2, which are respectively provided at their upper edges, with bars 27 and 28, extending upwardly therefrom, and having a series of short teeth or dents 27' and 28' thereon, see Fig. 1. The teeth or dents 27' and 28' correspond in location with the dents of the reed 9, and are adapted to enter into or between the warps 10 and 11, when the bars 25 and 26 are raised, as shown in Fig. 2. The bar 25 is suitably secured to the upper ends of the arms or levers 29, which have their hubs 29' fast on a rock shaft 30, see Fig. 1. Two of the levers 29, as shown in Fig. 1, have in this instance downwardly extending arms 29'', which have adjustably secured to their lower ends studs 31, see Figs. 3 and 4, to which are pivotally connected the rod heads 32, on the adjustable connecting rods 33. The other ends of the rods 33 are provided with rod heads 34, which are pivotally connected to one end of angle levers 35, the hubs 35' of which are each loosely mounted on a stud 36 on a stand 37, which is secured to the girt 2. The other arms of the angle levers 35 are each provided with a roll, which travels on the periphery of cams 38, see Fig. 1, which cams are fast on the bottom

shaft 24. A helically coiled contraction spring 39, see Fig. 1, which is attached at one end to a lug 40' on a stand 40, and at its other end to an arm 41, which has its hub 41' secured on the rock shaft 30, acts to hold the bar 25 on arms 29 in engagement with the bar 26.

Through the operation of the cams 38 on the bottom shaft 24, and the angle levers 35, and intermediate connections to the arms 75 29'' on the shaft 30, a rocking motion is communicated to said shaft 30 at predetermined times, which causes the bar 25 on arms 29 to be moved away from the bar 26, as shown in Fig. 4. The rock shaft 30 is in this instance loosely mounted in sleeves or hubs 42', which have extending upwardly therefrom the arms 42, which are adapted to carry the bar 26 and the comb 28 thereon. The hubs 42' are provided with journals 85 42'', see Fig. 2, which are pivotally mounted on the yoke shaped ends of the upwardly extending swinging arms 43. The lower ends of said arms 43 are pivoted on studs 44 on the yoke shaped heads 45, which in this instance are secured to the upper ends of downwardly extending guide rods 46, see Fig. 1. The guide rods 46 are suitably held and loosely guided in the bosses 47' on the stands 47, which are secured to the braces 48 95 of the loom. The heads 45 are in this instance provided on one side thereof with lugs 45', see Fig. 1, which carry studs 49, to which are pivotally connected the rod heads 50 on the upper ends of adjustable connecting rods 51. The lower ends of the rods 51 are provided with rod heads 52, which are pivotally connected to one end of levers 53, see Fig. 2. Each of the levers 53 has its hub 53' loosely mounted on the stud 36 on the stand 37, see Fig. 1. The other arms of the levers 53 carry rolls, see Fig. 2, which rolls are adapted to travel on the periphery of cams 54 fast on the bottom shaft 24. The two cams 54 operate the two levers 53, to cause the combs 27 and 28 to be raised and lowered at predetermined times.

The hub 42' of one of the arms 42, as shown at the right in Fig. 1, has extending downwardly therefrom a lug 42'', to which is pivotally connected the rod head 55 on one end of the connecting rod 56. The other end of the connecting rod 56 is provided with a rod head 57, which is adjustably connected, through a slot 58' in one end of an angle lever 58, to said angle lever 58. The angle lever 58 has its hub 58'' loosely mounted on a stud 59 on a stand 60, see Fig. 2, which is secured to the brace 48. The other arm of the angle lever 58 has pivotally connected thereto a rod head 61, see Fig. 1, on the upper end of the vertically extending rod 62. The lower end of said rod 62 is provided with a rod head 63, which is pivotally connected to one arm of an angle lever 125 64, see Fig. 2, which is secured to the brace 48. The other arm of the angle lever 64 has pivotally connected thereto a rod head 65, see Fig. 1, on the upper end of the vertically extending rod 66. The lower end of said rod 66 is provided with a rod head 67, which is pivotally connected to one arm of an angle lever 130 68, see Fig. 2, which is secured to the brace 48.

64, see Fig. 2. The hub 64' of the angle lever 64 is loosely mounted on a stud 65, secured by a set screw 66' in a boss 66'' on a stand 66, which is secured to the girt 2. The 5 other arm of the angle lever 64 has a roll 67 thereon, see Fig. 2, which travels in this instance on the periphery of a cam 68, which is fast on the bottom shaft 24.

The operation of the cam 68 and the angle lever 64, through intermediate connections to the hub 42' on the rocking shaft 30, communicates a sliding motion to said shaft 30, and the combs 27 and 28 thereon, in either direction, to cross the warps, as will be hereinafter described.

The helically coiled contraction spring 69 has one end connected to a lug 58'' on the upright arm of the angle lever 58, and its other end to a stationary part of the loom, 20 not shown, and acts to hold the roll 67 on one arm of the angle lever 64, in contact with the periphery of the cam 68.

The operation of our improved mechanism in connection with the drawings and 25 the above description, will be readily understood by those skilled in the art, and the method of weaving the pile fabric of the Persian rug type, is briefly as follows: As shown in Fig. 5, two sets of warps 10 and 30 11, (warp 11 is shaded to distinguish it from warp 10), have formed the shed, and the two combs 27 and 28 are raised to cause the teeth or dents 27' and 28' thereon to be inserted between the lower warp threads 11, 35 which in this instance will occupy the position shown in Fig. 6.

The combs 27 and 28, through the mechanisms above described, will be moved sidewise, and in the direction indicated by the 40 arrow in Fig. 7, and the lower warps 11, which are normally parallel to the upper warps 10, as shown in Fig. 6, are moved with the combs 27 and 28 for the distance of two dents of the reed 9, to cross the warps 45 10, as shown in Fig. 7. At the same time the whip roll 13, see Fig. 2, is operated to cause the lower warps 11 to be slackened, and allow of the side movement referred to. On the next operation, the combs 27 and 28 50 are raised higher, through the mechanism above described for raising and lowering said combs, and the upper warps 10 are lowered by the shedding mechanism, as shown in Fig. 8, in order to enter between the dents or teeth 27' and 28' on the combs 27 and 28. The combs 27 and 28 are now 55 moved sidewise, by mechanism above described, in the direction indicated by arrow f, in Fig. 9, and cause the warps 11 and the 60 warps 10 to be moved with said combs 27 and 28 for the distance of one dent of the reed, and to occupy the crossed positions shown in Fig. 9. At the same time the whip roll 12, see Fig. 2, is operated to slacken the 65 upper warps 10. While in this position the

rocking of the shaft 30, in the manner above described, causes the comb 27 to be moved away from the comb 28 for a certain distance, as shown in Figs. 4 and 10. This movement causes the central part of the 70 warp threads 10 and 11, between the combs 27 and 28, to be held parallel to each other, as shown in Fig. 11, and leaves an opening between the crossed warp threads, to allow the entrance of the tuft yarn tubes or needles 7, carrying the tuft yarns 6, as shown in Fig. 10, and the passage of the tuft yarn 6 between the crossed warps 10 and 11. The combs 27 and 28 are now lowered, causing 75 the dents or teeth 27' and 28' to move out from between the warps, allowing the warps 10 and 11 to return to their normal parallel position, the whip rolls 12 and 13, see Fig. 2, being operated to tighten the warp threads 10 and 11, and the tuft yarn tubes or needles 80 85 7 are then raised, and the pile or tuft yarns 6, which are left between the warps 10 and 11, will be crossed sidewise, as shown at 6' in Fig. 14. The tuft yarn tubes or needles 7 carrying the tuft yarns 6 are moved downwardly a second time between the warps 10 and 11, as shown in Fig. 13, to finish the knot, as shown in Fig. 14, and a cutter, not shown, is drawn across the fabric, on the underside thereof, to cut or sever at 6'', see 90 Fig. 13, the pile yarns 6 extending from the lower end of the tubes or needles 7, and the tubes or needles 7 are raised and withdrawn from between the warps, and filling threads, not shown, are inserted in the usual way to 95 100 bind the pile yarn knots.

The operation above described is performed for each transverse row of pile yarn tufts in the fabric.

It will be understood that the details of 105 construction of our improvements may be varied if desired.

We have shown in the drawings and described herein one form of means or mechanism for crossing some of the warp threads 110 relative to the other warp threads, and forming openings with parallel sides between the crossed warp threads for the insertion of the tuft yarn needles, but we do not limit ourselves to the particular means or mechanism referred to as any other suitable means, or mechanism may be employed for crossing some of the warp threads relative to the other warp threads, and forming openings with parallel sides between the crossed warp 115 threads for the insertion of the tuft yarn needles or tubes.

Having thus described our invention, what we claim as new and desire to secure by Letters Patent is:-

1. In a loom for weaving textile fabrics, warp threads, a warp parting device, to engage the warp threads between the reed and the fell of the fabric, and means to operate said warp parting device, to cross some of 125 130

4

the warp threads relative to the other warp threads, and form openings with parallel sides between the crossed warp threads, for the insertion of the tuft yarn tubes or needles.

5. In a loom for weaving textile fabrics, warp threads, means, including a comb having teeth, to engage the warp threads between the reed and the fell of the fabric, and 10 means to operate said comb, to cross some of the warp threads relative to the other warp threads, and form openings with parallel sides between the crossed warp threads, for the insertion of the tuft yarn tubes or 15 needles.

6. In a loom for weaving tufted fabrics, warp threads, means, including two combs, having teeth to engage the warp threads between the reed and the fell of the fabric, and 20 movable relative to each other, and means for operating said combs, to cross some of the warp threads relative to the other warp threads, and form openings with parallel sides between the crossed warp threads, for 25 the insertion of the tuft yarn tubes or needles.

7. In a loom for weaving tufted fabrics, the combination with the warp threads, of a warp parting device, to engage some of the 30 warp threads between the reed and the fell of the fabric, and means for operating said warp parting device, to cross said warp threads relative to the other warp threads, and hold the crossed warp threads apart, to 35 form openings with parallel sides between the warp threads, for the insertion of the tuft yarn tubes or needles.

8. In a loom for weaving tufted fabrics, warp threads, means, including two combs 40 having teeth, to engage the warp threads between the reed and the fell of the fabric, said combs movable longitudinally and movable laterally, to cross some of the warp threads relative to the other warp threads, 45 and form openings with parallel sides between the crossed warp threads, for the insertion of the tuft yarn tubes or needles, and means for operating said combs.

9. In a loom for weaving tufted fabrics, 50 the combination with the warp threads, of two combs having teeth to engage said warp threads, between the reed and the fell of the fabric, and means to move said combs to move some of the warp threads to one side 55 of their normal position, and move some of the warp threads in an opposite direction, to one side of their normal position, and means to separate the combs, to provide openings through the warps between the

combs, for the insertion of the tuft yarn 60 tubes or needles.

10. In a loom for weaving tufted fabrics, the combination with the warp threads, of two combs having teeth to engage said warp threads, between the reed and the fell of the 65 fabric, and means to move said combs to move one half the warps for a distance of two dents of the reed, to one side of their normal position, and to move the other half of the warp threads in the opposite direction 70 for the distance of one dent of the reed, to one side of their normal position, and means to separate the combs, to provide openings through the warps between the combs, for the insertion of the tuft yarn 75 tubes or needles.

11. In a loom for weaving tufted fabrics, the combination with the warp threads, and means for slackening and tightening said warp threads at predetermined times, of 80 two combs having teeth to engage said warp threads, between the reed and the fell of the fabric, and means to move said combs, to move some of the warp threads to one side of their normal position, and move some of 85 the warp threads in an opposite direction to one side of their normal position, and means to separate the combs to provide openings through the warps between the combs, for the insertion of tuft yarn tubes 90 or needles.

12. In a loom for weaving tufted fabrics, the combination with the warp threads, of two combs having teeth to engage said warp threads, between the reed and the fell of the 95 fabric, means to raise the combs to engage the lower warps in a shed, means to move the combs endwise after the lower warps are engaged, and means to slacken said warps during the movement of said combs, means 100 to move the combs higher to engage the upper warp threads, and means to move the combs in an opposite direction to cross the warp threads, and means to tighten the first mentioned warp threads, and means to slacken the second mentioned warp threads, 105 means to separate or move the combs apart, to provide openings in the warps between the combs, for the insertion of the tuft yarn tubes or needles, and means to lower the 110 combs out of engagement with the warps, to allow them to return to their normal position, and means for tightening the warps.
